UNITED STATES PATENT OFFICE.

JOHN F. KOLLA, OF HOLLAND, MICHIGAN, ASSIGNOR TO HOLLAND FURNACE COMPANY, OF HOLLAND, MICHIGAN, A CORPORATION OF MICHIGAN.

FURNACE HUMIDIFIER.

Application filed February 24, 1925. Serial No. 11,026.

This invention relates to a humidifier construction primarily adapted for use with hot air furnaces. It is designed that the usual water pan used with furnaces of this character shall be eliminated, and the water which is to supply moisture to the heated air going from the furnace shall be furnished in a predetermined quantity to the humidifier construction all, or the greater portion, of the water being evaporated in such construction, while any excess over what is evaporated may be carried through an overflow to the outside of the furnace in one form of my invention, or to the ash pit where it is absorbed by the ashes in another form thereof.

It is an object and purpose of the present invention to construct a humidifier which may be made, preferably, as an integral part of the fire pot casting, this resulting in economy in manufacture as the cost of production is increased very little and only to the extent of the added material which is required. A further object of the invention is to provide a humidifier construction which does not obstruct the air space within the outer enclosing casing of the furnace so that the circulation of air is not interfered with in any manner. A still further object of the invention is to construct a humidifier with which a greatly increased quantity of water may be vaporized and delivered to the heated air, the principle of the humidifier in this invention being much more effective for evaporation of water by reason of the large surface of water presented from which the water vapor may arise, coupled with the elimination of a large volume or body of water with a relatively small evaporating surface such as is common with water pans. Many other objects and purposes of the invention together with novel constructions and arrangements of parts for attaining the same will appear fully and in detail as understanding of the invention is had from the following description taken in connection with the accompanying drawings, in which,

Fig. 1 is a fragmentary vertical section through the outer casing of the lower part of a hot air furnace, the inner heating construction being shown in elevation.

Fig. 2 is a horizontal section through the construction shown in Fig. 1.

Fig. 3 is a fragmentary enlarged vertical section substantially on the plane of line 3-3 of Fig. 2.

Fig. 4 is a view similar to that shown in Fig. 1, with parts of the inner construction broken away and shown in section, illustrating a different form of construction embodying my invention, and

Fig. 5 is a horizontal section therethrough.

Like reference characters refer to like parts in the different figures of the drawings.

The furnace in its construction includes a lower ash pit casting 1, above which the fire pot casting 2 is located and supported. Above the fire pot the various other sections of the inner structure of the furnace are located including the combustion chamber dome, a portion of which appears in Figs. 1 and 4. The ash pit casting, at its front side, is formed with forwardly extending substantially vertical sides 3 which are integrally connected at their upper edges by a cross member or top 4, preferably inclining downwardly and inwardly as indicated in Fig. 4. The casing surrounding the ash pit, fire pot and other heat radiating structure includes a front plate 5 of cast metal and a substantially cylindrical sheet metal enclosing casing 6 to which the plate 5 is connected. The plate 5 is utilized for the mounting of the various doors closing the entrance to the fire pot and ash pit, the ash pit door being shown at 7.

In the form of construction shown in Figs. 1 and 2 a water receiving and holding trough is cast integral with the ash pit casting. This trough includes a bottom 8 and a substantially vertical side 9 cast integral with one side 3 of the forward projection to the ash pit, the same being integrally continued around the ash pit and substantially to the other side 3 of said forward projection, the bottom 8^a and the vertical side 9^a of the trough around the cylindrical portion of the ash pit being continuations with the bottom 8 and side 9 integral with the side 3. Preferably this trough inclines downwardly around the ash pit, being substantially of spiral form as best shown in Fig. 1. At its lower end the trough is closed by a vertical end 10. An opening 11 may be made through the ash pit casting so that water delivered to the trough which is not

evaporated in its progress down the trough and which collects at the lower end thereof to the level of the opening 11, is drained therethrough into the ash pit and is absorbed in the dry ashes within said ash pit.

A spout 12 extends through the plate 5, its inner end being directly over the upper end of the trough and its outer end being outside of the furnace casing. Water is delivered to this spout from a pipe 13, the amount thereof being controlled by a manually operated valve 14. The supply of water to the pipe 13 may be from any convenient source, such as a water main or a receptacle adapted to contain water located in an upper plane; or if desirable it may be connected directly to the hot water coil of the furnace, such coils being common installations in nearly all furnaces.

The water dropping into the spout 12 is carried and delivered to the trough on the ash pit. The amount delivered is relatively small and is subject to control so that in practice, when the furnace is operating at or near capacity, all of the water delivered to the trough is evaporated by reason of the heat and the fact that it is spread out over a wide area. The trough is heated by reason of its connection to the ash pit casting and it also receives heat directly radiated from the fire pot above. During the daytime when the fire within the furnace is at greatest intensity all of the water delivered to the trough is evaporated. At night when the fire is checked, the heat for evaporation is lessened and the surplus water runs to the lower end of the trough and eventually, when it reaches the level of opening 11, is drained into the ash pit and absorbed by the ashes. This is a feature of advantage in that dust in the ashes is eliminated and the air going to the fire through the ash pit is more or less changed into water vapor, this being a well-known advantageous feature in burning fuels such as are used in furnaces, aiding in the combustion of the fuel.

In Figs. 4 and 5 a somewhat different form of construction embodying the invention is shown. On the top 4 of the forward projection of the ash pit, a water holding receptacle is made by casting upwardly extending side ribs 15 integral with the top 4 and also curved and spaced apart cross ribs 16 and 17 which connect the outer and inner ends of the vertical ribs 15, as best shown in Fig. 5. The water is delivered from a pipe 18 to the receptacle thus made, and the amount is controlled by a manually operated valve 19 interposed in the pipe 18. Water in the shallow receptacle thus made is subjected to heat from the fire pot and a large portion thereof evaporated. What is not evaporated collects in the receptacle and eventually may fill the receptacle to a predetermined level at which it is designed to

overflow to an auxiliary humidifier construction similar in many respects to that shown in Figs. 1 and 2.

Back of the rear vertical cross rib 17 a shallow trough 20 is made in the top 4 of the forward projection of the ash pit. This trough is extended beyond the sides of the water receiving receptacle and around the ash pit at the upper edges thereof, a vertical side 21 for the trough being continued from the rib 17 entirely around the ash pit. The trough after it leaves the forward projecting portion of the ash pit is deepened and has a bottom 22 which is located at a level lower than the bottom of the trough 20. Water reaching the predetermined level in the receptacle in which it is collected overflows into the trough 20. I have shown a pipe 23 to carry this overflow but it is evident that this pipe is not necessary as the water may flow through the opening in the rib 17 to the trough 20 from which it is carried around the ash pit casting. During the time that the heat given off by the furnace is abated, excess water collects in the deeper portions of the trough and when it has reached a certain level may be carried outwardly through an overflow drain pipe 24 extending from the side 21 of the trough through the casing 6, as shown in Fig. 5.

With both of these constructions a heavy evaporation of water within the furnace casing may be had and with an insurance that water is supplied at all times for humidifying the heated air delivered from the furnace outer casing. Both forms of constructions shown are made by merely casting additions on to the ash pit casting with little or no increase in cost of production. A large evaporating area for water is provided. The water is in close proximity to the fire pot which is ordinarily the hottest element in the entire furnace construction, insuring heavy evaporation. Proper humidifying of the air from the furnace is thus attained and insured. In the form of construction shown in Figs. 1 and 2, the excess of water over what is evaporated is carried into the ash pit and moistens the ashes with the resultant advantages coming therefrom, above described. The constructions are very practical, economical to manufacture and in every way a great improvement over the old and well-known water pan system of furnace humidifying. The invention is defined in the appended claims and is to be considered as comprehensive of all forms of structure coming within their scope.

I claim:

1. In a furnace, an ash pit casting of substantially cylindrical form having a projecting portion at the front side thereof, said projecting portion having vertical sides and a top connecting the sides, ribs cast integral

with said top and extending upwardly therefrom to form a receptacle in which water may be contained, and a trough around the ash pit adjacent the upper end thereof into which water overflowing from the receptacle is received, substantially as described.

2. A construction containing the elements in combination defined in claim 1 combined with means for continuously supplying a predetermined amount of water to said receptacle, substantially as described.

3. A construction containing the elements in combination defined in claim 1 combined with means for continuously supplying water to the receptacle, and a drainage opening formed in the trough above the bottom thereof through which excess of water may be drained from the trough when it reaches

the level of said opening, substantially as described.

4. In a furnace, an ash pit casting of substantially cylindrical form but tapering inwardly from its lower end toward its upper end, a trough cast integral with the ash pit casting at the upper end thereof, said trough comprising a bottom extending outwardly from the ash pit for a short distance and a vertical side spaced from the ash pit, said vertical side being located substantially within a vertical projection of the lower end of said ash pit, and means for supplying water to said trough, substantially as described.

In testimony whereof I affix my signature.

JOHN P. KOLLA.
